UNITED STATES PATENT OFFICE.

EDGAR J. QUIGGLE, OF SHELBY, OHIO.

CURTAIN STRETCHER.

Application filed June 4, 1927. Serial No. 196,426.

My invention relates to improvements in curtain stretchers and has particular reference to an adjustable and foldable frame upon which lace curtains and the like are 5 stretched after being washed.

Heretofore adjustable frames for the purposes described have been arranged so as to be capable of being taken apart for the purpose of storing the frame when not in use, 10 but one of the objects of my invention is to provide a simple and inexpensive means whereby the frame may be folded into a compact package without requiring that the parts of the frame be disassembled one from the 15 other.

Another object of my invention is to provide a strong and simple curtain pin, adapted to be slidably positioned on the said frame, and constructed from a single piece of sheet 20 metal stamped and formed as hereinafter described.

Another object is to provide a plurality of legs adapted to be securely, yet adjustably, fastened to said frame.

With the above and other objects in view, 25 my invention consists in the combination and arrangement of parts hereinafter described and claimed, and more particularly illustrated in the preferred embodiment as shown in 30 the accompanying drawings, wherein

Figure 1 is a top plan view of a portion of a curtain stretcher, as constructed according to my invention, the portions cut away being similar to those shown.

Figure 2 is an end view of a curtain stretcher as disclosed in Figure 1, but supported in a slanting position by the adjustable legs.

Figure 3 is an enlarged top plan view of one of the latch joints.

Figure 4 is a sectional view of one of the latch joints, unlatched and partly opened, along the line 4—4 of Figure 3.

Figure 5 is a transverse sectional view through one of the frame bars, showing the 45 method of positioning the slidable curtain pins.

Figure 6 is a perspective view of one of the slidable curtain pins.

Figure 7 is a perspective view of a portion 50 of one of the legs, showing the forked end thereof.

Figure 8 is a top plan view of the frame in its folded position.

Figure 9 is a side view of Figure 8.

Referring now more particularly to the drawings, 10 indicates a pair of longitudinal

frame bars, each of which is broken at a suitable point in its length and hinged as by latch joints 11, so as to permit of the same folding upon themselves, and 12 indicates a pair of 60 cross frame bars, each of which is also broken at a suitable point in its length and also hinged as by latch joints 11 so as to permit of the same folding upon themselves. The longitudinal bars 10 and the cross bars 12 65 have slots 13 parallel with the sides of the bars and extending for a portion of the length thereof, and bolts 14 having wing nuts 15 are adapted to engage said slots and lock the cross bars upon the longitudinal bars in any 70 desired position. Legs 16, having one end provided with angularly bent forks 17, are adapted to be engaged by any of the bolts 14. The angularly bent forks 17 are formed with two planes of engagement with said 75 bolts; one plane 18 being parallel with the longitudinal axis of the leg, and the other plane 19 being angularly disposed to the longitudinal axis of the leg, whereby the leg may be mounted on the frame angularly 80 thereto as shown in Figure 2, or the leg may be mounted on the frame so as to be parallel thereto, as shown in full lines in Figure 9.

The longitudinal bars 10 and the cross bars 12 are formed to a similar cross section, as 85 shown in Figure 5, and comprise a rectangular body portion 20, having the slots 13 passed perpendicularly therethrough; the said body portion 20 is rabbeted or cut away upon its inner edge and throughout the length thereof 90 so as to form a cutout 21; the base 22 of the cutout 21 has a longitudinally extending vertically disposed groove 23 near its outer edge, and at the inside corner of the cutout 21 the wall 24 thereof has a longitudinally extending horizontally and inwardly disposed groove 25. The curtain pins 26 are adapted to slidably rest upon the base 22 of the cutout, and to slidably engage the groove 23 as by 95 dependent tongues 27, and also to slidably engage the groove 25 as by a horizontally disposed tongue 28; the vertically disposed tongue 29 is adapted to slidably engage the wall 24 of the cutout. Positioned intermediate of the dependent tongues 27 is a vertically 100 extending point 30 adapted to engage the curtain or other article placed in the frame. As shown in Figure 6 the curtain pin 26 is constructed of a single piece of sheet metal stamped and formed as heretofore described. 110

The latch joints 11 comprise spaced side plates 31 connected by a cross piece 32. A

bolt 33 having wings 34 at one end and a round head 35 at the other end threadedly engages the cross piece 32 intermediately of the side plates 31. The opposing ends of the frame bars, as at 37, where the said bars are broken to form the joints, are pivoted to the side plates 31 so as to be spaced apart as at 36 to permit the said bolt 33 to pass thereinbetween.

10 In the embodiment shown in the drawings, the opposing ends 37 of the frame bars, where the said bars are broken to form the joints, are enclosed in U-shaped members comprising side pieces 38 disposed parallel to the side-plates 31 and pivoted thereto as by pins 39, and so that the end pieces 40 of the said U-shaped members which are in opposing relation when the joint is closed are spaced apart so as to permit the said bolt 33 to pass thereinbetween. The end piece 40 of the said U-shaped member is provided with a lip 41 so disposed as to be oppositely of the cross piece 32 when the joint is closed; the said lip 41 has a notch 42 adapted to receive the said bolt 33 whereby the said lip 41 may engage the underside of the head 35 of the said bolt. When the joint is closed, as shown in Figure 3, the lip 41 positioned as described on the one end 37 of the frame bar is adapted to co-act with the lip 41 similarly positioned on the other and opposing end 37 of the frame bar so as to engage the bolt 33 between them, whereby the head 35 of the said bolt is adapted to lock the said opposing ends of the frame bar in aligned relation to each other as by turning the bolt by means of the wings 34 aforesaid so as to cause the said bolt to pass inwardly the latch joint 11.

40 When my invention is in use, the latch joints being in their closed position and the opposing ends of the bars being locked in aligned relation as described, the said bars may be placed in any desired position relative to one another as heretofore described.

45 When it is desired to fold up the frame, how-

ever, the bolts 33 are caused to pass outwardly the said latch joints 11 so as to unlock the opposing end of the bars, as shown in Figure 4, and the wing nuts 14 on the bolts 14 are loosened, whereupon the legs 16 may be positioned so as to be parallel with the said bars, and the said bars folded upon themselves, as shown in Figures 8 and 9, so as to occupy a relatively small space.

50 When the invention is in use, as described, and it is desired to stretch a curtain or other article in the frame, the curtain pins 26 may be slid upon the bars so as to be most suitable for holding the curtain, and the curtain having been stretched within the frame, the 55 frame may then be placed in a slanting position as described so as to favor the circulation of air through the curtain and quicken the drying thereof. Fixed pins 26^a may be employed, if desired, on certain portions of 60 the frame, in addition to the slidable pins 26.

I claim:

1. In a bar for a curtain stretcher having opposed and coacting portions adapted to be positioned in aligned relation to each 70 other, and spaced side plates pivotally engaging said opposed and coacting portions, a cross piece connecting said side plates, a locking means threadedly engaging said cross piece and adapted to pass between said opposing and coacting portions, and lips formed on said opposing and coacting portions adapted to engage said locking means.

75 2. A curtain holder for a curtain stretcher comprising a stamping having one portion 80 of one edge bent so as to form a perpendicularly disposed guide, the other portion of said edge extending parallel to said holder, and the other edge having a perpendicular pin disposed in the same direction as said 85 guide and also having a perpendicular finger disposed oppositely to said pin.

In testimony whereof I affix my signature.

EDGAR J. QUIGGLE.
